UNITED STATES PATENT OFFICE

2,075,274

FUEL STOKER

Samuel M. Darling, Oak Park, Ill., assignor to
 Darling Automatic Stoker Co., a corporation of
 Illinois

Application June 13, 1934, Serial No. 730,407

3 Claims. (Cl. 110—115)

The present invention is directed generally to a novel and improved construction of a fuel stoker of the portable type which is capable of being automatically or manually controlled.

5 The primary object of the present invention is to provide a simple, compact and efficiently operated portable type of fuel stoker.

A further object of the invention is to provide a novel and improved construction of fuel stoker with means for automatically and evenly 10 distributing the fuel on the fire bed.

A still further object of the invention is to provide a novel and improved construction of fuel stoker in which a rotor feed is provided which 15 performs the double function of discharging the fuel into the firebox and furnishes a sufficient current of air in delivering the fine coal dust into the firebox so that the same is burned in suspension.

20 A still further object of the invention is to provide a novel and improved fuel stoker in which the blades of the rotary feeder are hinged and in addition thereto, one of the blades is formed of a flat surface while the others have various degrees of curvature so as to effectively raise the 25 coal stream in its delivery to the distributor.

A yet further object of the invention is to provide a novel and improved fuel stoker in which an adjustable bottom is provided in the coil chute for raising or lowering the delivery of the coal 30 stream.

These and other objects are accomplished by providing a construction and an arrangement of the various parts in the manner hereinafter 35 described and particularly pointed out in the appended claims.

Referring to the drawings:

Fig. 1 is a top plan view of a fragmentary portion of a boiler firebox (partly shown in cross-section) with my improved fuel stoker positioned in operative position with respect thereto;

Fig. 2 is a cross sectional view taken on the broken line 2—2 in Fig. 1;

Fig. 3 is an enlarged fragmentary view of the 45 driving connections for my improved fuel stoker;

Fig. 4 is a cross sectional view taken on the line 4—4 in Fig. 3;

Fig. 5 is a cross sectional view taken on the line 5—5 in Fig. 1;

50 Fig. 6 is an enlarged fragmentary cross-sectional view of the rotary feeder;

Fig. 7 is an enlarged fragmentary perspective view of the fuel spreader;

Fig. 8 is a perspective view of the driving connections for oscillating the spreader;

Fig. 9 is an enlarged detailed view showing the adjustable plate for raising or lowering the fuel stream; and

Fig. 10 is a bottom plan view of the same.

The primary feature of the present invention is to provide a novel, compact and portable type of stoker to automatically and continuously feed the fuel into the fire box of a furnace in a uniform and evenly spread manner over the fire so as to secure the maximum efficiency from the fuel. The invention also contemplates the control for the amount of fuel fed to the firebox by manual or automatic means, the latter of which may be controlled by well known arrangements such for example as the boiler pressure or by thermostatic control at some selected point.

In illustrating one form of my invention, I have shown the same in connection with a conventional form of boiler, a fragmentary portion of which is generally indicated by the reference character 11. This boiler 11 is provided with the usual firebox 12, grate 13 and front wall 14. The inner walls of the firebox are provided with the usual refractory material generally indicated by the reference character 15. The front wall 14 of the furnace is provided with the usual fuel doors 16 and ash doors 17.

My improved portable stoker comprises a box like main frame generally indicated by the reference character 18, which is suitably mounted on four caster wheels 19, so that the same may be removed from or positioned in operative position in front of the firebox. Mounted in the box like main frame structure 18 is a hopper, generally indicated by the reference character 20, which is in substantially the form of an inverted pyramid with the apex thereof supported substantially in the center of the main frame 18, as shown in Fig. 2 of the drawings. Mounted in suitable bearings in the main frame, adjacent the apex of the hopper is a shaft 21 to which two spaced apart sprocket wheels 22 are secured. Extending from one side of the hopper 20 is an elevator housing, generally indicated by the reference character 23. The bottom of this housing forms an extension of one of the bottoms of the hopper and is relatively narrow as compared with the width of the hopper proper as clearly indicated by reference to Fig. 4 of the drawings. Mounted in suitable bearings, in a housing 23, is a shaft 25. Secured to the shaft 25 within the housing and spaced with respect to each other, are two sprocket wheels 26. Trained about these sprocket wheels 26 and the lower sprocket wheels 22 are endless chains 27. Connecting the corresponding links of each of the

spaced apart chains 27 are elevator cleats 28. Mounted below the upper lap of the elevator chains is a supporting plate 29 which extends substantially the length of the elevator. Extending over the upper portion of the elevator belt and extending to a point short of the bottom of the hopper is a shield or housing 30. Positioned below the delivery end of the elevator housing 23 is a rotor and fan housing 31. Connecting the delivery end of the elevator housing 23 with the rotor and fan housing 31 is a discharge spout 32. (See Figs. 2 and 3.) Mounted on top of the elevator housing 23 is a variable speed transmission mechanism generally indicated by the reference character 33. Mounted on the shafts 35 and 42 within the variable speed transmission housing are the conventional axially adjustable pulley sections 33' which are geared together by means of a belt 34'. (See Figs. 3 and 4.) This variable speed transmission mechanism is of any well known construction. Mounted on top of the variable speed transmission mechanism 33 is an electric motor 34 which is operatively geared to and drives a shaft 35 of the variable speed transmission mechanism 33 through the sprocket wheels 36 and 37 secured respectively to the motor shaft and shaft 35. These sprocket wheels are geared together by a chain 38. Mounted adjacent the motor 34 in suitable bearings 39 is a supplemental drive shaft 40. Secured to one end of the shaft 40 is a large sprocket wheel 41 which in turn is operatively driven by a sprocket wheel 44 secured to a shaft 42 of the variable speed transmission mechanism 33. The sprocket wheels 41 and 44 are 35 geared together by the chain 45. The speed of the elevator may be manually controlled or automatically controlled by the steam pressure or thermostatically. This elevator is driven through the shaft 40 by means of the sprocket wheel 46 which 40 is geared to and operatively drives a chain 47 trained about a sprocket wheel 48 secured to the shaft 25 outside the elevator housing 23. The variable speed drive mechanism is provided with the usual operating lever 49 to which the usual 45 connections may be made for either thermostatically controlling the feed of the fuel or for controlling the feed of the fuel by the boiler pressure.

One of the primary features of the present invention includes in addition to a novel means for distributing the fuel evenly over the fire bed, also a novel means for delivering the fuel to the spreader with a sufficient blast of air so that the fuel or coal dust is delivered to the firebox in such a manner that it is burned in suspension. This novel arrangement includes a rotor, generally indicated by the reference character 50, which comprises a shaft 51 mounted in suitable bearings located in the opposite sides of the rotor housing 31. The shaft 51 is driven by the shaft 35 through the medium of a sprocket wheel 35' secured to the shaft 35 and a sprocket wheel 36' secured to one end of the shaft 51. These sprocket wheels are geared together by a chain 37'. Secured to the shaft 51 are spiders 52. Secured to the periphery of these spiders is a cylindrical screen 53. Pivoted outside the screen and to each of the arms of the spiders 52 are blades 54, 55, 56 and 57. The swinging blade 54 is a flat blade, while the blades 55, 56 and 57 are of gradual increasing curvatures. These various types of curved blades have a tendency to raise the stream of the fuel in its delivery to the spreader herein-after described. Arranged about the axis of the shaft 51 on each end of the rotor housing 31 are

four equally spaced apart openings 58. These openings are arranged in the rotor housing within the periphery of the rotating screen 53 and permit the rotor to draw air inwardly so as to furnish a draft or current of air in the delivery of the fuel and dust being discharged against the spreader, thereby permitting the fuel dust to be burnt in suspension within the firebox. Extending tangentially from the rotor housing 31 is a fuel discharging chute, generally indicated by the reference character 59. Mounted in a depressed recess 59' and extending tangentially from the bottom curved portion of the rotor housing 31 is an adjustable spring plate 60 which has one end thereof secured to the housing by means of rivets 61 and the free end thereof bent downwardly as shown at 62. This free end extends through a slot 63 and is adjustable with respect to the bottom by a set screw 64. This adjustable plate 60 permits the operator to raise or lower the height of the fuel stream in accordance with the type of fuel being discharged in the fuel box. In other words, when the fuel has a considerable quantity of larger lumps it is desirable to raise the fuel stream to secure a more effective spread of the fuel on the fire bed.

Another essential feature of the present invention includes the novel fuel spreading device which under most circumstances, may be satisfactorily used as a stationary spreader while under certain other conditions, I deem it advisable in order to secure more satisfactory and uniform spread of the fuel in the firebox to oscillate the same. This novel spreading device comprises an oscillatable distributor, generally indicated by the reference character 65. This oscillatable distributor comprises a normally horizontal shaft or bar portion 66 which has a downwardly projecting stud 67 on which it is journaled in a socket 68 of a bearing support, which in turn, is secured to the top of the chute 59. This horizontal bar portion 66 has a right angularly and vertically extending arm 69 to which is secured or formed integrally with, three sets of distributor blades, generally indicated by the reference characters 70, 71 and 72. The upper pair of blades diverge forwardly and outwardly in the arc of a relatively small circle, while the second set or pair of blades diverge forwardly and outwardly on a relatively larger arc of a circle while the third set or pair of blades, which are the lowermost ones diverge forward and outwardly on a still larger curve or arc of a circle. From an examination of Figs. 2 and 7 of the drawings, it will be observed that the relatively short blades are located at the top where the greater portion of the fuel being discharged is of the lighter variety while the intermediate pair of blades 71 and lower pair of blades 72 are positioned substantially at the center of the mouth of the distributing chute. At this point, these relatively larger curved blades effect a uniform distribution of the major portion of the larger lumps of fuel. It will also be noted that there is a substantial opening between the lower pair of blades 72 and the bottom of the chute in order to permit the relatively large lumps to be discharged without being effected by the spreader so that the same may be discharged to the furthermost end of the firebox. The other end of the bar 66 is provided with a flat portion, as shown at 73. Located in the end of this flat portion is a longitudinally extending slot 74 to which is slidably and pivotally connected by means of a pin 75, an arm 76. The crank arm 76 is formed integrally with or secured to the

lower end of a vertical bar 71. The lower end of the bar 71 is provided with a stud 71' which is pivotally mounted in a bearing support 78 secured to the upper portion of the fuel chute 59. The upper end of the bar 71 is bent at right angles as shown at 78' and journaled by means of a pin 79' in a bracket 79. One end of the bracket 79 is secured to the elevator housing 23. The bent portion of the bar 71 extends laterally to form an arm 80, the outer end of which is provided with a longitudinally extending slot 82 which is adapted to pivotally and slidably receive a pin 83 secured to one end of a pitman connection 84. The other end of the pitman connection is pivotally connected by means of a pin 85 to a crank 86 secured to one end of the upper elevator shaft 25.

The operation of my improved fuel stoker is as follows:

Let us assume that the fuel stoker is positioned in operative position so that the fuel discharge spout 59 extends into the opening in the firebox in the manner disclosed in Figs. 1 and 2 of the drawings and that the electric motor is connected to operatively drive the operating parts thereof in the manner previously described. In this connection it will be understood that the variable speed drive mechanism may be manually controlled or automatically controlled by the steam pressure or thermostatically in any well known manner, and as the elevator elevates the fuel from the hopper it is discharged from the delivery end of the elevator into the rotor which is connected to be driven at a relatively high speed so as to deliver the fuel stream with sufficient velocity to deliver the larger lumps of fuel at the furthermost end of the fire bed. In so doing, it will be understood that the rotor in addition to functioning as a discharge means for delivering the fuel into the fire bed, performs the additional function of a fan for drawing the air axially through the openings in the side walls of the rotor housing and thereby deposits the fuel dust into the firebox where it is burned in suspension. As this action is taking place, the fuel spreading device 65 is oscillated from one side to the other by the operative connections 84, 80 and 71 as clearly shown in Fig. 1 of the drawings, to effect a uniform and even distribution of the fuel in the fire bed. In this connection it will be observed by reason of the position, length and different curvatures of the various pairs of blades, as well as the oscillating action of the spreader, a uniform and even distribution of the fuel discharged through the chute is secured.

While in the above specification I have de-

scribed one embodiment which my invention may assume in practice, it will of course, be understood that modification may be made without departing from the spirit and scope of the invention as expressed in the following claims:

What I claim is my invention and desire to secure by Letters Patent is:

1. A fuel stoker for a firebox comprising a frame, a hopper in the form of an inverted pyramid mounted on said frame, an endless elevator mounted in said hopper, a rotor mounted below the delivery end of said elevator, said rotor comprising a plurality of differently curved blades, a housing encasing said rotor for receiving the fuel from said elevator, a chute extending from said housing into said firebox there being openings adjacent the axial center of said rotor in said housing through which air is drawn by said rotor for effectively discharging the fuel in the stream under air pressure through said chute, and a plurality of pairs of differently curved blades located in the path of the stream of fuel for effecting a uniform distributing of the fuel in said firebox.

2. A fuel stoker for boiler firebox comprising a portable frame, a hopper mounted on said frame, elevating means mounted in said hopper, a rotary impeller located below the delivery end of said elevating means, a housing encasing said impeller and the delivery end of said elevating means, a discharge chute connected tangentially with said housing and extending into said firebox, and an automatically actuated oscillatable fuel spreader located at the end of said chute and including a plurality of pairs of differently curved blades mounted on a common pivot, said pairs located at different elevations with respect to each other for evenly distributing the fuel in said firebox.

3. A fuel stoker for a firebox comprising a frame, a hopper mounted on said frame, means mounted in said hopper for elevating the fuel from said hopper, a housing positioned below the delivery end of said elevating means and adapted to receive fuel therefrom, a rotary impeller mounted in said housing below said elevating means for discharging the fuel from said housing, a fuel spreader mounted on said housing for distributing the fuel including pairs of differently diverging blades mounted on a common pivot, said pairs located at different elevations with respect to each other, and a vertically adjustable plate located between said impeller and said spreader for raising and lowering the fuel stream discharged by said impeller.

SAMUEL M. DARLING. 55
